UNITED STATES PATENT OFFICE.

MILTON D. STOCKING, OF LINDENWOOD, ILLINOIS.

AIR OR STEAM COUPLING FOR RAILWAY-CARS.

SPECIFICATION forming part of Letters Patent No. 395,089, dated December 25, 1883.

Application filed May 14, 1883. Serial No. 273,793. (No model.)

To all whom it may concern:

Be it known that I, MILTON D. STOCKING, a citizen of the United States, residing at Lindenwood, in the county of Ogle, State of Illinois, have invented certain new and useful Improvements in Air or Steam Couplings for Railway-Cars, of which the following is a specification.

The object of this invention is to construct 10 a coupling designed for use, in connection with steam or air, on railway-cars, that will be automatic in its operations, and is more particularly designed for use in connection with freight-cars to enable the engineer to 15 control his train at all times.

This invention consists in a two-part coupling, each part carrying a valve which is automatically opened as the two parts come together, and are automatically closed as the 20 two parts separate; also means for adjusting the coupling either horizontally or vertically.

In the accompanying drawings, Figure 1 is 25 an isometrical representation of a portion of a truck of a railway-car with my improvements in place thereon. Fig. 2 is a side elevation showing the brace-rods and their adjustable connections. Fig. 3 is a side elevation of the coupling-heads in their horizontal 30 positions about to be coupled. Fig. 4 is a side elevation showing the heads coupled. Fig. 5 is a vertical central section on dotted line *a*, Fig. 4, showing the connections of the steam-pipes.

The truck represented in the drawings is of 35 the usual construction, but may be any of the known varieties, of which I will only mention the bolster portion 1, supported upon the wheels. Brackets 2 are fixed to the lower edge of the bolster 1. In these brackets is 40 supported a two-armed brace, 3, composed of the arms 4 and 5. The ends of these brace-arms are in round-bar form and project through the brackets 2 and receive a screw-nut, 6. Between the nut 6 and the bracket 2 is wound a coil-spring, 7, the action of which 45 tends to hold the brace against the bearing for the purpose of horizontal adjustment. Washers 8 are placed on the rounded end portion of the brace-arms forward of their 50 bracket-support, for a purpose to appear hereinafter.

A rod, 9, is connected at one end to the bol-

ster 1 by means of a bracket, 10, secured thereto. The other end of this rod 9 is screw-threaded, and is bent downward and passes 55 through the brace 3 near its free end. Adjusting-nuts 11 are placed one on each side of the brace 3, by means of which the free end of the brace 3 may be vertically adjusted.

The coupling-heads to operate the valves 60 consist, essentially, of the lever portions 12, pivotally connected to the free end of the brace 3, and are held from horizontal movement by being connected between the arms 13 and 14 by a bolt passing through the arms 65 and a slot, 15, in the lever portion 12. The said lever portion 12 is provided with a pin, 12^a, which serves to support the head in a horizontal position. The free ends of the lever portions are produced in clutch form to 70 engage with each other. Each of these heads is provided with like jaws, 16, projecting from the side of each head. These jaws serve to guide the heads into engagement with each other, and the pins 17 are the center upon 75 which they turn, and when in the position shown in Fig. 4 they will be locked together, and can only be released when they attain a horizontal position, or nearly so, as shown in Fig. 3.

Each of the heads is provided with a tubular opening, 18, and a hose or other suitable connection, 19, connects the coupling-head with the air or steam supply employed to operate the brakes. These openings 18 communicate 85 with an opening, 20, extending lengthwise of the coupling-head, which communicates with a transverse opening, 21, in the free or meeting ends of the coupling-heads, forming a continuous tubular opening. The inner faces 90 of these heads at the point where the openings communicate with each other are provided with a packing, 22, of rubber or other suitable material. As the heads are brought together, this packing will form a steam or 95 air-tight connection and permit the passage of the steam or air from the hose of one head through the openings out through the hose of the other head.

An oscillatory valve, 23, is placed in the 100 opening 20, between its end openings, and is connected on the outside with a segmental operating device. (Shown at 24, Figs. 3 and 4.) The valves are operated by means of a

projection, 25, fixed on each head on the side opposite to that at which the valves are situated, so that the projection on one head will engage the valve of the other head. By this arrangement when the heads are about to engage each other the valve will stand closed, as shown in Fig. 3, thereby giving the engineer complete control of the cars attached to the locomotive. When the cars come together by reason of the inclined portions 26, the tendency will be to throw the heads upward, and in this movement the heads will interlock and the projections 25 will engage the valve and turn and open it, as shown in Fig. 4. A shield, 27, is so placed on each head as to protect the valve and its operating device. A spring, 28, is secured at one end to a stud, 29, projecting from the brace 3, coiled around the pivot-bolt connecting the head and brace, 20 its end passing through an eye, 30, and resting on the shield. The action of the spring is to hold the head in a horizontal position, but will yield and permit the heads to couple.

In adjusting my coupling for use on different-height cars, the vertical adjustment is attained by means of adjusting-nuts 11 on the bent end portion of brace-rod 9. The horizontal adjustment is accomplished by placing washers 8 before either bearing as may be required to bring the heads in proper position to interlock. The slotted connection of the heads with the brace-support permits the heads to retain their position in the opposite endwise movement of the cars permitted by 35 the spring action of the car-coupling.

This coupling is supported on the truck below the car-coupling and will not interfere with the working of the coupler.

Cars provided with this coupling device 40 will, when brought together automatically, couple the steam or air pipes leading from the steam or air supply, and when standing alone the coupling-heads, by the action of the spring, will be held in their horizontal position, and 45 the valves on both ends will be closed, and will remain so until brought in contact with a like coupling on another car, and as soon as a car leaves the main train the valves of both heads will be automatically closed, 50 thereby giving the engineer complete control of his train.

I claim as my invention—

1. In a steam or air brake coupling, the combination, with two coupling-heads pivoted to 55 a support to swing in a vertical direction and provided with steam air-ducts and a projection carried by each head, of valves provided with arms to engage said projections, whereby the valves are opened and closed by the swing-

ing of the heads upon engaging and disengaging one another, substantially as set forth.

2. In an air or steam brake coupling, the combination of a coupling-head, an intermediate support connecting the head with the truck of a car, the head having a swinging connection with the intermediate support, and a spring having its opposite ends connected with the head and intermediate support, substantially as set forth.

3. In an air or steam brake coupling, the combination, with the coupling-head pivoted to swing in a vertical direction and provided with a steam-duct and a projection, of a valve provided with arms to engage the said projection, whereby the valves are opened and 75 closed by the swinging of the head upon engaging with an adjacent head, substantially as set forth.

4. In an air or steam brake coupling, the combination, with the coupling, of a support 80 having a longitudinal yielding engagement with the truck of the car, and pivoted to said coupling-head, and a brace connected to said truck and having a vertical adjustable connection with said support, substantially as 85 set forth.

5. In an air or steam brake coupling, the combination, with the valved coupling-heads and the supports to which they are pivoted to swing vertically, each of said heads produced 90 in clutch form and provided with laterally-projecting pins, as 17, and springs secured to said supports and to the said coupling-heads, the arrangement being such that when the coupling-heads are brought together the pins 95 will engage the clutch portions and throw the heads in a vertical position, and when the heads are disengaged the springs will return the heads to a horizontal position, substantially as set forth.

6. In an air or steam brake coupling, the combination, with the coupling-heads, of adjustable supports having a pivoted connection with said heads, substantially as set forth.

7. In an air and steam brake coupling, the 105 combination, with the support provided with branches, as 4 and 5, each having a longitudinally-yielding connection with the truck, of the coupling-head pivoted to the free end of said support and a brace pivotally connected 110 to the truck of the car with one end and with the other end vertically adjustably connected to the said support.
